UNITED STATES PATENT OFFICE.

FREDERICK RICHARDSON, OF NEW BEDFORD, MASSACHUSETTS.

IMPROVEMENT IN BOOT-HEELS.

Specification forming part of Letters Patent No. 77,529, dated May 5, 1868.

To all whom it may concern:

Be it known that I, FREDERICK RICHARDSON, of New Bedford, in the county of Bristol and State of Massachusetts, have invented a new and Improved Reversible Boot-Heel; and I do hereby declare that the following is a full, clear, and exact description thereof, which will enable those skilled in the art to make and use the same, reference being had to the accompanying drawings forming part of this specification.

This invention relates to a new and improved method of constructing heels for boots or shoes, whereby they are rendered much more durable than those made in the ordinary manner; and the invention consists in forming the heel so that its center or wearing-portion may be reversed, as will be hereinafter be more fully described.

Figure 1 represents a view of the bottom of the heel. Fig. 2 is a cross-section of Fig. 1 through the line *xx*.

Similar letters of reference indicate corresponding parts.

In carrying out my invention, I attach to the heel of the boot, by screws or in any substantial manner, a metallic flange, *a*, which corresponds on its outside with the size or diameter of the boot-heel. Within this flange I confine a reversible recessed central plate, *c*, which is attached to the boot-heel by a central screw, or by any other suitable means. The recesses on each side of this plate are filled with leather or other suitable material, as seen at *dd* in the drawing. Upon the flange

a, at the front and rear, or on opposite sides, there are small lugs or catches, *e*, which, when the plate *c* is in place, enter recesses in the outer flange of the plate, and serve to keep the plate in place, and prevent it from slipping after one side is worn off, or after it has been reversed. *e'* represents the boot-heel, and *f* is the central screw.

The leather or other suitable material with which the recesses in the plate *c* are filled, is held in place by india-rubber, or any suitable adhesive material. More than one screw can be used for holding the plate to the heel if desired.

It will be seen that when one side of the plate becomes worn it may be turned over, and the other side be presented as the wearing-surface. A very material advantage to be derived from the use of these reversible heels is, they may be changed from one boot to the other, thus keeping the wearing-surfaces uniform. The outside flange *a* and the plate *c* may be made of iron or any other suitable material, either cast or wrought.

Having thus described my invention, I claim as new and desire to secure by Letters Patent—

The reversible plate *c*, formed substantially as described, in combination with the flange *a* and the filling *d*, and applied to a boot or shoe heel, as set forth and specified.

FREDERICK RICHARDSON.
